UNITED STATES PATENT OFFICE.

LÜDWIG MEIR, OF MÖCKERN, NEAR LEIPZIG, GERMANY.

CASE OR BOX FOR HOLDING A PHOTOGRAPHIC-PRINTING OUTFIT FOR PRODUCING POST-CARDS.

SPECIFICATION forming part of Letters Patent No. 766,368, dated August 2, 1904.

Application filed December 3, 1903. Serial No. 183,623. (No model.)

To all whom it may concern:

Be it known that I, LÜDWIG MEIR, a subject of the German Emperor, residing at 1 Albertstrasse, Möckern, near Leipzig, Germany, have invented certain new and useful Improvements in Cases or Boxes for Holding Photographic-Printing Outfits for Producing Post-Cards; and I do hereby declare the following to be a full, clear, and exact description of the invention, such as will enable others skilled in the art to which it appertains to make and use the same.

This invention relates to a receptacle containing a number of removable cases in which all the implements requisite for producing illustrations on post-cards from sketches and the like by photographic printing can be conveniently arranged.

By means of the invention a person traveling is enabled to take with him in a small space all the articles required for copying sketches or pen-and-ink drawings from nature by photographic printing.

Figure 1 is a longitudinal section; Fig. 2, a transverse section of the receptacle with the cases inserted therein. Figs. 3 to 5 are illustrations of the cases.

The receptacle *a*, with cover *a'*, which is pushed over the same, is made of strong waterproof material, the side *b* being so connected with the bottom of the receptacle that it can be turned outward. (Dotted lines in Fig. 2.)

In the receptacle *a* *a'* the trays *d* *d'* *d''* are inserted. Each of these is intended for a particular purpose and is closed by a removable cover or lid *d'''*, which is of the same depth as the tray, so as to entirely inclose the same when placed thereon, as shown in Figs. 1 and 2. The tray *d*, Fig. 3, is divided into four different compartments, of which the largest, *g*, holds the block of paper sheets on which the sketches are made, while the narrow compartment *h* is intended for the pencils, brushes, and similar drawing utensils. The compartment *i* holds the sponge and the compartment *k* the eraser.

The cases or trays (illustrated in Figs. 4 and

5) are each divided into two equal compartments, the compartments *m* *m'*, Fig. 4, being intended for the printed post-cards, the compartments *o* *o'* for the copying-frame and the press. The compartments *m* and *m'* have their walls *m''* inclined outwardly, as shown, and each end of the tray containing said compartments is formed with a notch or recess *m'''*. By inclining the said walls *m''* the edges of the stack of cards are held on a bevel or incline, so that said edges project one beyond the other from the bottom to the top of the stack, thus allowing a portion of each card to project a sufficient distance to be readily grasped, and by providing the notches *m'''* the edges of the cards may be engaged and removed one by one by inserting the finger in a notch and under the exposed edge of each card, as will be readily understood.

What I claim as my invention, and desire to secure by Letters Patent, is—

A box or case for the purpose described, comprising a receptacle having a series of trays arranged in superposed relation therein, each of said trays being partitioned to form compartments, the partition and end walls of one of said trays being inclined to hold the edges of stacks of cards in the compartments formed between the same on a bevel, and said end walls having finger-recesses, and the partition of another tray consisting of spaced walls providing a chamber between compartments formed thereby and formed with finger-recesses, each of said trays being provided with a removable cover, the said receptacle having a hinged door adapted when opened to permit individual withdrawal of any of said trays, and a cover for the receptacle adapted when applied to hold said door closed, substantially as described.

In testimony whereof I affix my signature in presence of two witnesses.

LÜDWIG MEIR.
